CLAIM

The ornamental design for a bottle, as shown and described.

DESCRIPTION

FIG. 1 is a front elevational view of a bottle showing my new design, the rear elevational view being a mirror image thereof; and, FIG. 2 is a top, front and left side perspective view thereof, the top, rear and right side perspective view is the same.

The bottom of the bottle is flat and unornamented.

FIG. 1

FIG. 2
